[57] CLAIM

The ornamental design for a beverage tumbler, as
shown and described.

DESCRIPTION

FIG. 1 is a side elevational view of a beverage tumbler
showing my new design;

FIG. 2 is a top plan view thereof;

FIG. 3 is a bottom plan view thereof; and

FIG. 4 is a side perspective view of a modification of
my new design for a beverage tumbler.

FIG-2

FIG-1

FIG-3

FIG-4
